UNITED STATES PATENT OFFICE.

CHARLES BERTRAM, OF CLEVELAND, OHIO, ASSIGNOR TO THE MORREAU COMPANY, OF CLEVELAND, OHIO, A CORPORATION.

PORTABLE ELECTRIC LAMP.

1,147,205.

Specification of Letters Patent.

Patented July 20, 1915.

Application filed April 8, 1915. Serial No. 19,878.

To all whom it may concern:

Be it known that I, CHARLES BERTRAM, citizen of the United States, residing at Cleveland, in the county of Cuyahoga and 5 State of Ohio, have invented certain new and useful Improvements in Portable Electric Lamps, of which the following is a specification.

- This invention relates to portable electric lamps such as those adapted to stand on tables or the like, and especially to the means for supporting the lamp bulb and shade, and for holding the same at any desired angle.
- 10 15 The fixture comprises or includes a standard and a turning or swivel joint, so constructed that the electric wires extend through the same and are concealed, and the joint is provided with stops which limit the 20 swing of the lamp to a certain extent. The structure has also certain other advantages with respect to strength and ease of assembling, as will more fully appear from the following description and the accompanying drawings.

In the drawings, Figure 1 is a side elevation of the lamp. Fig. 2 is a cross section on the line 2—2 of Fig. 1. Fig. 3 is a section on the line 3—3 of Fig. 2.

25 In the drawings, 6 is the base of the lamp and 7 a tubular standard which branches at the top into two arms 8 which are also hollow. These are bowed outwardly to accord with the shape or design of the lamp shade employed, and the design may be varied as desired. Each arm 8 terminates at the upper end in a hollow circular cheek piece or shell 9, the outer wall of which is closed, and 30 35 on its inner face has a circular flange 10 around an opening, and these flanges form a bearing for a ring or circular shell 11 having circular openings at each side into which the flanges project, whereby the ring is retained in position and may be turned between the cheek pieces 9. Projecting from the ring is a tubular nipple 12 threaded to receive the socket of the lamp 13 as 40 45 also any suitable holder for the shade 14.

The cheek pieces are clamped against the 50 55 sides of the ring or shell 11 by means of a through bolt 13 having a head 14 at one end and a locking nut 15 and ornamental nut 16 at the opposite end. The bolt is adjusted to produce sufficient friction between the meet-

ing surfaces to hold the lamp in any position to which it may be swung.

It is desirable to restrict the movement of the lamp within certain limits, and for this purpose each flange 10 has a projecting finger 17 at the top thereof in position to form a stop by contact therewith of the inner end 18 of the nipple which projects inwardly into the ring 11. The lamp therefore cannot be swung or turned around completely, which might disarrange the electrical connections. The electric wires 20 are led through the standard of one of the arms 8 and thence through the parts of the joint to the lamp, said wires being thus wholly concealed.

For use at writing desks or the like the lamp can be adjusted to any convenient angle, and the fixture has an ornamental or artistic appearance as well as practical advantages. By removing the bolt 13 the 75 cheek pieces 9 can be sprung apart sufficiently to permit the middle part or ring 11 to be slipped in or out, whereby the parts can be readily assembled or removed without breaking any fixed joints.

What I claim as new is:

1. An electric fixture comprising a pair of arms with hollow cheek pieces at the ends thereof, said pieces having inwardly projecting circular flanges, a hollow ring 85 mounted to turn on said flanges, between said cheek pieces, and having a nipple for a lamp socket, and a bolt extending through said cheek pieces and ring and clamping the latter frictionally between the former, and 90 electric circuit wires extending through one of said arms and cheek pieces, the ring, and the nipple.

2. An electric fixture comprising a pair of hollow arms terminating in hollow cheek 95 pieces closed at their outer sides and open at their inner sides and each having a circular flange at the inner side thereof, extending around the opening, a hollow turning ring located between said cheek pieces and fitting 100 upon said flanges, a stop finger projecting from one of the flanges, a lamp socket nipple projecting outwardly from the ring and also having a part projecting into the same in position to strike said finger and stop the 105 turn of the ring, and a clamping bolt connecting the cheek pieces and extending through the ring.

3. An electric fixture comprising a stand-
ard, a pair of bowed arms branching there-
from and terminating in opposite hollow
cheek pieces open at their inner sides, a ring
5 located between the cheek pieces and having
a slip joint therewith, whereby the ring may
be inserted or removed by springing the
arms and cheek pieces, a clamping bolt ex-
tending through the ring and cheek pieces,

and a nipple for a lamp socket, projecting 10
from the ring.

In testimony whereof I affix my signature
in presence of two witnesses.

CHARLES BERTRAM.
